(57) **CLAIM**

The ornamental design for a heat shield as shown and described.

DESCRIPTION

FIG. 1 is a front-top-left perspective view of a heat shield, according to a first embodiment of the present invention.

FIG. 2 is a front view of the heat shield of FIG. 1.

FIG. 3 is a rear view of the heat shield of FIG. 1.

FIG. 4 is a left side view of the heat shield of FIG. 1.

FIG. 5 is a right side view of the heat shield of FIG. 1.

FIG. 6 is a top view of the heat shield of FIG. 1.

FIG. 7 is a bottom view of the heat shield of FIG. 1.

FIG. 8 is a front-top-left perspective view of a heat shield, according to a second embodiment of the present invention.

FIG. 9 is a front view of the heat shield of FIG. 8.

FIG. 10 is a rear view of the heat shield of FIG. 8.

FIG. 11 is a left side view of the heat shield of FIG. 8.

FIG. 12 is a right side view of the heat shield of FIG. 8.

FIG. 13 is a top view of the heat shield of FIG. 8; and,

FIG. 14 is a bottom view of the heat shield of FIG. 8.

The broken lines in FIGS. 1-7 illustrate portions of the heat shield that form no part of the claimed design.
